UNITED STATES PATENT OFFICE.

REGINALD E. GRIFFITHS AND WILLARD G. SMITH, OF NEW YORK, N. Y.

ICE CARRIER.

Application filed February 9, 1923. Serial No. 618,086.

To all whom it may concern:

Be it known that we, REGINALD E GRIFFITHS and WILLARD G. SMITH, citizens of the United States, residing at New York 5 city, State of New York, have invented certain new and useful Improvements in Ice Carriers, of which the following is a specification.

This invention relates to an improved ice 10 carrier particularly designed for domestic use and seeks, as one of its principal objects, to provide a device whereby a housewife may conveniently carry a block of ice from a dumb waiter or the like to a refrigerator.

15 The invention has as a further object to provide a device so constructed that a block of ice may be readily slid into the device and as easily discharged therefrom.

And the invention has as a still further 20 object to provide a device which will be simple in construction and which may be produced at moderate cost so that the device may be placed upon the market at a cost within the financial reach of the average 25 purchaser.

Other and incidental objects will appear hereinafter.

In the drawings:

Figure 1 is a perspective view of our 30 improved ice carrier,

Figure 2 is a longitudinal sectional view through the device, and

Figure 3 is a transverse sectional view on the line 3—3 of Figure 2, looking in the direction of the arrows.

In carrying the invention into effect, we form our improved ice carrier with a preferably oblong scoop-shaped body having a flat bottom wall 10, spaced parallel side 40 walls 11, and a back wall 12 closing the body at its rear end and connected to the rear ends of the side walls by flaps or ears 13 riveted or otherwise secured to said side walls. Preferably, the body is formed from a single piece of suitable resilient sheet metal 45 bent to the desired shape and, as will be observed, the back wall is slightly higher than the side walls while said side walls are provided at their forward ends with sloping 50 edges so as to eliminate the presence of any

undesirable sharp angles at the mouth of the carrier. Riveted or otherwise secured to said sloping edges of the side walls as well as to the upper edges thereof and to the upper edge of the back wall 12, are channel 55 shaped binding strips 14 reinforcing said walls. Similarly secured to the bottom wall at its forward end is a channel shaped wear strip 15 which will not only serve to reinforce this wall but will also serve to prevent 60 premature injury thereto. Riveted or otherwise secured at their ends to the side walls are handles 16 which, as best shown in Figure 1, incline downwardly toward the forward ends of said walls. Thus, as will 65 be seen, the device is exceedingly simple in construction and may be readily produced.

As will now be readily understood in view of the foregoing, the carrier may be rested at its forward end upon the shelf of a dumb 70 waiter or other surface, when a block of ice may be readily slid into the carrier. This done, the handles 16 of the device may be grasped and, due to the inclination of said handles, the device will, when the handles 75 are so grasped, normally be tilted rearwardly, as suggested in Figure 2, to dispose the handles in horizontal position. It should be noted that the position of the handles is such that the middle portions of 80 the handles are situated in advance of the center of gravity of the body and that, consequently, the carrier will be held in such tilted position naturally and without any effort of the user. This will, of course, prevent the block of ice from sliding forwardly 85 out of the carrier so that the block of ice may be conveniently carried within the device to be deposited in a refrigerator or the like, it being easily possible, as will be 90 appreciated, to slide the block of ice out of the carrier by simply tilting the carrier forwardly. Thus, by the use of the device, a block of ice may be easily handled without likelihood of dropping the ice as well as without dripping, the device being preferably 95 constructed to contain any water collecting therein as the ice melts.

Having thus described the invention, what is claimed as new is:

An ice carrier comprising a body having bottom, back and side walls, the front and top being open to accommodate a block of ice, and handles secured upon the side walls and inclined in the longitudinal direction thereof with their middle portion in advance of the center of gravity of the body

whereby, when the handles are held in horizontal position, the body will be normally tilted rearwardly to retain the ice. 10

In testimony whereof we affix our signatures.

REGINALD E. GRIFFITHS. [L. S.]

WILLARD G. SMITH. [L. S.]
